CONTROL FOR AN ELECTRIC BLANKET

Burton Kelly, Western Springs, Ill., assignor to Sunbeam Corporation, Chicago, Ill., a corporation of Illinois

Filed Nov. 1, 1967, Ser. No. 9,240

Term of patent 14 years

(Cl. D26—13)

Fig. 1.

Fig. 2.

FIG. 1 is a perspective view of a control for an electric blanket showing my new design;

FIG. 2 is a top plan view thereof;

FIG. 3 is a side elevational view, the opposite side being substantially a mirror image thereof; and

FIG. 4 is an enlarged fragmentary sectional view taken on line 4—4 of FIG. 2.

I claim:

The ornamental design for a control for an electric blanket, as shown and described.
